US00D872784S

(12) **United States Design Patent** (10) Patent No.: **US D872,784 S**
(45) Date of Patent: ** Jan. 14, 2020

(54) **CUTTING INSERT FOR A ROTARY CUTTING MACHINE TOOL**

(71) Applicant: **MITSUBISHI HITACHI TOOL ENGINEERING, LTD.**, Tokyo (JP)

(72) Inventors: **Fumihiko Inagaki**, Narita (JP);
Yasuhiro Kiuchi, Narita (JP);
Yoshiyuki Kobayashi, Narita (JP)

(73) Assignee: **Mitsubishi Hitachi Tool Engineering, ltd**, Tokyo (JP)

(**) Term: **15 Years**

(21) Appl. No.: **35/505,615**

(22) Filed: **Mar. 26, 2018**

(80) **Hague Agreement Data**

Int. Filing Date: **Mar. 26, 2018**

Int. Reg. No.: **DM/102512**

Int. Reg. Date: **Mar. 26, 2018**

Int. Reg. Pub. Date: **Sep. 7, 2018**

(30) **Foreign Application Priority Data**

Nov. 16, 2017 (JP) 2017-025585

(51) LOC (12) Cl. **15-09**

(52) U.S. Cl.

USPC **D15/139**

CPC **B23C 5/207** (2013.01)

(57) **CLAIM**

The ornamental design for a cutting insert for a rotary cutting machine tool, as shown and described.

DESCRIPTION

1. Cutting insert for a rotary cutting machine tool

1.1 : Right-bottom perspective view

1.2 : Left-bottom perspective view

1.3 : Left-top perspective view

1.4 : Right-top perspective view

1.5 : Front

1.6 : Top

1.7 : Bottom

1.8 : Right

The rear view is identical to the front view; the left view is identical to the right view. The broken lines depicting the remainder of the cutting insert show features that form no part of the claimed design.

1 Claim, 8 Drawing Sheets
